UNITED STATES PATENT OFFICE.

ELMER C. NIELSEN, OF RAWLINS, WYOMING.

WATCH-WINDING ATTACHMENT.

1,386,351.

Specification of Letters Patent.

Patented Aug. 2, 1921.

Application filed November 14, 1919. Serial No. 338,063.

To all whom it may concern:

Be it known that I, ELMER C. NIELSEN, a citizen of the United States, residing at Rawlins, in the county of Carbon and State of Wyoming, have invented certain new and useful Improvements in Watch-Winding Attachments, of which the following is a specification.

This invention relates to improvements 10 in watch winding attachments especially adapted to be applied to main spring winders.

An important object of this invention is to provide a watch winding attachment which 15 may be readily applied to a main spring winder and which may be sold as a part of the main spring winder so as to increase the utility and salability of the same.

A further object of this invention is to 20 provide a watch winding attachment for main spring winders having novel means for engaging the winding stem of the watch so that when the winding of the watch is completed the stem will lose its binding contact 25 with the device, whereby over winding of the watch is prevented.

A further object of the invention is to provide a device of the class described which is simple to use, of highly simplified construction and cheap to manufacture.

Other objects and advantages of the invention will be apparent during the course of the following description.

In the accompanying drawing, forming a 35 part of this application and in which like numerals are employed to designate like parts throughout the same,

Figure 1 is a side elevation of a main spring winder having the improved attachment applied,

Fig. 2 is a detail section through the attachment applied,

Fig. 3 is a fragmentary perspective of the attachment.

In the drawing wherein for the purpose 45 of illustration is shown a preferred embodiment of the invention, the numeral 5 generally designates a main spring winder having its lower portion provided with a shank 6 which is reduced, as indicated at 7, for providing an attaching lug adapted to be received between the jaws of a watchmaker's vise. The upper portion of the device is provided with aligned barrels 8 and 9, the barrel 9 rotatably receiving an operating crank 10 having a handle 11 and provided with a

fixed collar 11' retaining said crank against axial displacement toward the barrel 8. As is well known, these devices are employed for winding the main springs of watches prior 60 to fitting them within a watch case. In this particular style of device the main spring engaging and supporting means are connected to the forward end of the shaft or crank 10 whereby the rotation of the crank 65 causes the spring to be wound.

To provide for the attachment of the improved watch winding attachment the main spring engaging and supporting means are detached from the forward end of the shaft 70 10 and the forward barrel 8. The improved watch winder includes an arbor 12 having its rear end portion provided with a longitudinally extended socket 13 receiving the reduced forward end portion 14 of the shaft 75 or crank 10. The reduced forward end portion 14 of the crank is held within the socket by a set screw 15 which seats against a recess in the reduced end portion 14 for causing the rotation of the arbor with the crank. The 80 intermediate portion of the arbor 12 is enlarged to provide a bearing 16 which is rotatably extended through the barrel 8 and is held within the same by a locking sleeve 17. As will be noted with reference to Fig. 2, the 85 sleeve or collar 17, which is secured to the shaft by a set screw 18, engages the rear side of the bearing 16 and the rear side of the collar 8 so that undue longitudinal movement of the arbor is prevented. The forward 90 portion of the arbor is provided with a socket 19 which is of a greater diameter than the bearing 16 and engages the adjacent side of the barrel 8 for coacting with the collar 17 in securing the arbor in position. The cylindrical socket 19 is provided with a filling 95 20 of partly or fully cured rubber which may be cemented or otherwise secured in position and which is provided in its outer side with a recess 21 conforming in curvature to the 100 curvature of the stem 22 of a watch 23.

After one or more watches have been repaired and it is desired to wind the same, the stems 22 may be inserted into the recesses 21 for providing frictional contact between 105 the stem and the filling of rubber, whereby when the crank 10 is manually rotated the socket 19 will also be rotated for winding the watch. The rubber filling provides a frictional contact between the arbor 12 and 110 the stem to assure the complete winding of the watch. However, when the watch is

fully wound the frictional contact between the stem and the rubber will be insufficient to allow the watch to be overwound. In the event that the operator continues to rotate 5 the crank 10 after the watch is fully wound, the rubber will merely slip about the stem 22 and will not further rotate the latter.

This attachment may be sold with the original main spring winder or as a separate 10 part thereof. Also additional rubber fillings 20 may be provided when the original one becomes worn.

It is to be understood that the form of the 15 invention herewith shown and described is to be taken as a preferred example of the same and that such minor changes in arrangement and construction of parts may be made as will remain within the spirit of the invention and the scope of what is claimed.

20 Having thus described the invention, what is claimed is:

1. A watch winder comprising a standard having alined barrels, a crank including a 25 shaft received in one of said barrels, means retaining said shaft against axial displacement toward the other barrel, a winding arbor mounted in the other barrel and having means retaining the same against axial displacement toward the crank shaft, and co- 30 operating means carried by the shaft and arbor for detachably associating the two in driving relation.

2. A watch winder comprising a standard having alined barrels, a crank including a

shaft received in one of said barrels, a collar 35 on said shaft preventing axial displacement of the latter in the direction of the other barrel, a winding arbor mounted in the other barrel and having a watch winding socket bearing against the barrel to prevent axial 40 displacement toward the crank shaft, a collar on said arbor bearing against the other side of the same barrel to prevent displacement of the arbor away from the crank shaft axially, and coöperating means associating 45 the shaft and arbor in detachable driving relation.

3. A watch winder comprising a standard having alined barrels, a crank including a 50 shaft received in one of said barrels, a collar on said shaft preventing axial displacement of the latter in the direction of the other barrel, a winding arbor mounted in the other barrel and having a watch winding socket bearing against the barrel to prevent axial 55 displacement toward the crank shaft, a collar on said arbor bearing against the other side of the same barrel to prevent displacement of the arbor away from the crank shaft axially, a reduced end portion on the said 60 crank shaft, said arbor having a socket receiving said end portion, and a set screw in said arbor socket spotted into said reduced end portion whereby said arbor and crank shaft are detachably associated in 65 driving relation.

In testimony whereof I affix my signature.
ELMER C. NIELSEN. [L. S.]
